tion of Pennsylvania

Application December 18, 1947, Serial No. 792,590

4 Claims. (Cl. 178—44)

1. The invention herein described and claimed

relates to an improvement in wide-band micro-
wave systems. More particularly, the invention
provides means capable of effecting a substan-
tially reflectionless transition from a coaxial
mode of wave propagation to a helical mode, or
the reverse, over a very wide band of high radio
frequencies.

While the invention is adapted to be used in
various applications, the invention may be em-
ployed to particular advantage as a means for
coupling a traveling-wave amplifier tube to an
external coaxial-line transmission system.

The traveling-wave tube is a comparatively
new type of vacuum tube intended for use in the
communications art. The structure, theory of
operation, utilization and advantages of the
traveling-wave tube, particularly as an amplifier
of microwaves over a wide band of frequencies,
have been described in recent publications in-
cluding Electronics, November 1946, pages 90-92;
Wireless World, November 1946, pages 369-372;
Bell Laboratories Record, December 1946, pages
439-442; and Proceedings of the I. R. E., Febru-
ary 1947, pages 108-127.

As is described in the above publications, the
traveling-wave tube includes a helical trans-
mission line, or helix, whose function will be
readily understood from a brief description of
the operation of the tube. The tube's operation
depends upon the interaction between the electric
field of an electromagnetic wave and an electron
stream, both of which are traveling in the same
direction at approximately the same velocity.
While an electromagnetic wave ordinarily travels
at about the speed of light, electrons ordinarily
travel at a much slower speed. An extremely
high voltage, of the order of ten million
volts, would be required to project an electron
at a velocity approaching that of light. In order
that the velocity of the wave may be approxi-
mately the same as, and preferably a little slower
than, the velocity of electrons projected by a
voltage of reasonable magnitude, there is in-
cluded, within the evacuated envelope of the
traveling-wave tube, a helical transmission line,
or helix, whose principal function is to retard
the axial progress of the wave. It will be under-
stood that the wave continues to travel at approxi-
mately the velocity of light but that it follows the
turns of the helix, and in so doing travels a path
substantially longer than the axial length of the
helix. In some of the traveling-wave tubes now
being tested and used experimentally, the helical
path is thirteen times longer than the axis of

2.

the helix. In such case, the axial electric field
travels down the helix at about one-thirteenth
the speed of light. This is substantially the same
as the velocity of electrons projected by a poten-
tial of the order of sixteen hundred volts.

The traveling-wave tube is particularly suited
for employment as an amplifier of microwaves
over a wide band of frequencies, the width of the
operating band being largely determined, at the
10 present state of the art, by the impedance
matches at the input and output ends of the
helix, that is, by the impedance matches at the
junctions between the ends of the tube's helical
transmission line and the external transmission
line system.

In accordance with the present invention, mod-
ifications are provided, both to the prior art helix
and to the prior art coaxial-line terminating sec-
tion, which permit the traveling-wave tube to
20 be coupled into a microwave coaxial transmission
line system without substantial reflection occur-
ring, at either the input or output junctions, over
a very wide band of ultrahigh and superhigh
frequencies.

25 In accordance with the broader aspects of the
present invention, improved transition means
are provided for effecting transfer of electro-
magnetic wave energy from a coaxial line to a
helical line, or from a helical line to a coaxial line,
30 whether or not a traveling-wave tube is involved.

It is an object then of this invention to pro-
vide improved means for effecting transition
from a coaxial to a helical mode of wave propa-
gation, or the reverse, i. e., from a helical to a
35 coaxial mode of propagation.

It is another object of this invention to provide
improved means for accomplishing transfer of
electromagnetic wave energy from a coaxial line
to a helical line, or the reverse.

40 It is another object of this invention to pro-
vide improved means for accomplishing transfer of
electromagnetic wave energy from a coaxial line
to a helical line, or the reverse, without in-
curring substantial reflection at any frequency
45 within a wide band of ultrahigh and superhigh
operating frequencies.

Another object of this invention is to provide
improved means for coupling a helical transmis-
sion line directly to a coaxial transmission line
50 system, without employing frequency-sensitive
impedance-matching devices.

Another object is to provide, for a traveling-
wave tube, improved input and output connec-
tions suitable for connecting the external coaxial
55 system to and from the helix of the tube.

Another object is to provide means for substantially effectively matching, over a wide band of ultrahigh and superhigh frequencies, the impedances at the junctions between an external coaxial-line system and the input and output ends of the helix of a traveling-wave tube.

These and other objects, features and advantages of the present invention will become clear from a consideration of the following detailed description and of the accompanying drawing in which:

Figure 1 illustrates, in section, a traveling-wave tube and coaxial transmission line interconnected by means of the present invention, and

Figure 2 is an exploded elevational view of a portion of the structure of Figure 1.

Referring now to Figure 1, there is shown a traveling-wave tube 10 which includes a heater 11, cathode 12, accelerator anode 13, and collector anode 14. Heater 11, cathode 12 and accelerator anode 13 constitute a gun assembly, similar to that used in conventional cathode-ray tubes, for projecting a beam of electrons down the long barrel 22 of tube 10 toward the target or collector anode 14. The beam of electrons is indicated in the drawing by the dashed line 15.

In accordance with the present invention, the envelope of the improved tube 10 includes a pair of laterally projecting stubs, 18 and 19. One of the envelope stubs is located at the near end of barrel 22 just beyond the gun assembly, and the other is located at the far end of the barrel just ahead of the collector anode 14. Each of the envelope stubs, 18 and 19, tapers, in cone-shaped manner, to a point, P and P', respectively. In Figure 1, the angle at which stubs 18 and 19 meet the main barrel 22 of tube 10, is shown to be substantially ninety degrees, but other angles may be employed.

The helix 23, of the improved tube of the present invention, extends from point P to point P' by way of stub 18, main barrel 22, and stub 19. The helix may be supported within the envelope of the tube by any suitable means, as, for example, by a plurality of axially positioned rods of insulating material which in turn are supported by spacers of mica or other suitable material.

At the point P of entry to the tube, and at the point P' of exit from the tube, the conductor of the helix is completely without spiral, being in the form of straight conductors 23a and 23b, to which the glass envelope of stubs 18 and 19 is respectively sealed. Immediately after entry at point P, the straight conductor 23a begins to spiral in turns of constantly increasing diameter until the desired maximum diameter of the helix is attained. This preferably occurs at the large end of the cone-shaped portion of stub 18. Helix 23 then continues, preferably at constant diameter, along stub 18, makes a bend into main barrel 22, continues therewith to the intersection with stub 19, makes a bend into stub 19, and continues therewith until the cone-shaped portion of stub 19 is reached. Helix 23 then tapers, in spirals of constantly decreasing diameter, until the spiral completely disappears, and the helix conductor passes through the envelope at point P' in the form of a straight conductor 23b.

Except for the tapered portions described above, the helix is preferably of constant diameter and constant pitch. The pitch of the tapered portions may also be constant, if desired. At the junction of stub 18 with main barrel 22, the separation between adjacent turns of the helix, along the outer radius of the bend, may however

be slightly increased, and/or the diameter of the helical turns may be slightly varied, if necessary or desirable, to permit the electrons of the beam 15 to enter the core of the helix without appreciable obstruction from the helical conductor. It will be understood that the electron beam at this point is sharply focused and very small in cross-sectional area. At the junction between main barrel 22 and stub 19, the obstruction offered by the helix to the electrons, as they emerge from the core and proceed to the collector anode 14, may be slightly greater due to the fact that the electron beam is not so sharply focused at this point. Slightly greater obstruction is allowable at this point, however, since the desired transfer of energy from the electron beam to the traveling wave has been accomplished.

The electromagnetic wave W, which is to be amplified by means of the traveling-wave tube 10, is shown in the drawing to be traveling along coaxial line 24 in the direction indicated by the arrow. Except for the terminating section, to be described, coaxial line 24 is conventional and comprises an outer cylindrical conductor 25 and an inner conductor 26. Inner conductor 26, which is coaxially aligned within the outer cylindrical conductor 25, may be either solid or tubular. In the drawing, inner conductor 26 is shown to be tubular.

In accordance with the present invention, the conventional coaxial line 24 is connected to a coaxial line terminating-section 27, as by means of a threaded coupling collar 28. The coaxial line terminating-section 27 is shown to comprise two parts, 27a and 27b, each of which is equipped with a flange, 34 and 35, respectively. Flange 35 includes an over-lapping projecting rim which is threaded externally to receive a coupling collar 29, by means of which sections 27a and 27b are held together. Other forms of coupling may, of course, be used.

Housed within the coupled flanges 34, 35, is a disc-shaped insulator 36, of polystyrene or other suitable material, having a center hole 31 through which straight conductor 23a passes. The function of the disc-shaped insulator 36 is to maintain conductor 23a coaxially aligned within the outer cylindrical conductor of the terminating-section 27. The selected diameter of disc-shaped insulator 36 is a function of the dielectric constant of the material of which it is made. The diameter should be of such magnitude that no apparent discontinuity is offered to the electromagnetic wave W.

If the outside diameter of conductor 23a is smaller than the inside diameter of the tubular inner conductor 26 of the coaxial line 24, the tubular inner conductor of the terminating section 27a, is preferably tapered, as indicated in the drawing, to avoid having a sharp discontinuity at the point where inner conductor 26 joins conductor 23a.

The outer cylindrical conductor of section 27b terminates in a crown-like multi-pronged portion 32 whose length is preferably equal to the tapered portion of helix 23. In the drawing, the crown-like portion 32 is illustrated as having four equi-spaced V-shaped prongs but may have other configurations. For purposes of clear illustration, the drawing includes, in Figure 2, an exploded view of the crown-like portion 32 and of the tapered portions of the helix and tube-envelope stub.

The function of pronged portion 32 is to assist in achieving a substantially reflectionless transi-

tion from the radial electric field of the coaxial mode of wave propagation to the axial or turn-to-turn electric field of the helical mode. Observe that as the center conductor 23a of the coaxial line begins to spiral in turns of constantly increasing diameter, the spiral conductor moves closer and closer to the outer cylindrical conductor 32, and unless some form of compensation is provided, the capacitance between the inner spiraling conductor and the outer cylindrical conductor would steadily increase as the diameter of the spirals increased. In the structure shown in the drawing, the necessary compensation is provided by omitting portions of the outer conductor 32 at equally spaced points on the perimeter. The portions omitted are increasingly large in the direction of the helix and reach a maximum at the extremity 33 of the outer conductor 32, i. e., at the point where the spiraling inner conductor is just about to attain maximum diameter. Here the outer conductor comprises but four equi-spaced points of conductive material.

The transition means employed at the output end of the traveling wave tube, i. e., the means employed to connect the helix in stub 19 with the outgoing coaxial transmission line 30, is identical in construction to that employed at the input end of the traveling-wave tube, and just described above. The corresponding parts may be readily seen in the drawing. It is, therefore, believed to be unnecessary to further describe the output connection.

The length of the tapered portions of the helix, and of the crowned portions of the coaxial terminating section, at both the input and output ends, may be of the order of five wavelengths long, and preferably longer. In general, the longer the lengths of the tapered portions of the helix, and of the crowned portion of the coaxial outer conductor, the smoother the transition will be.

I have ascertained that, by means of the construction shown in the drawing and described above, an electromagnetic wave, having a coaxial mode of propagation, may be applied to the input end of a helical transmission line without substantial wave reflection occurring at any of the frequencies of an extremely wide band of ultrahigh and superhigh frequencies, e. g., a band of the order of several thousand megacycles or more wide. And, by the use of similar construction, the amplified wave may be removed from the output end of the tube's helical transmission line and applied to the outgoing coaxial transmission line without incurring substantial reflections over a band of similar width.

In my experiments, using relatively crude mechanical construction, the voltage standing wave ratio at the center of the band, for a band of frequencies extending from 2500 to 3500 megacycles, was only 1.15, and at the edge of the band was only 1.30. The standing wave ratio at frequencies outside the 2500-3500 mc. band should be correspondingly low, for the transition means of the present invention includes no resonant elements.

The discovery of means capable of coupling together a coaxial and helical transmission line, without experiencing substantial reflection of wave energy, is of particular importance in the case of traveling-wave tubes. For heretofore, the gain and efficiency of the traveling-wave tube as a wide-band microwave amplifier have been limited by the substantial reflections which have

occurred at some of the frequencies, either inside or outside, of the intended operating band. To prevent oscillations, the prior art traveling-wave tube has employed a helix constructed of material having such a high attenuation constant that energy, which is reflected at any particular frequency, will be attenuated to an extent greater, ordinarily, than the gain realized from the tube at that same frequency. The use, in the prior art traveling-wave tube, of a helix of high attenuation necessarily reduces the R.-F. power level at the output of the tube and hence reduces the gain and efficiency of the tube. The present invention, by eliminating substantial reflection of wave energy at substantially all frequencies of an extremely wide band, eliminates the necessity of employing a high attenuation helix. Consequently, the gain and efficiency of the tube is increased materially.

I have described my improved transition means as particularly applicable to a traveling-wave tube, since important advantages are derived from such application. It is to be understood, however, that the improved transition means of the present invention may also be employed in other applications. In general, the invention may be employed wherever it is desired to connect together a coaxial and helical transmission line without incurring substantial reflection of wave energy at substantially any frequency of a very wide band of high frequencies. For example, the helix, instead of being a part of a traveling-wave tube, may be employed as a matched delay line. Or the helix may be employed as a matched attenuator or power absorber, or as a power measuring device. Other applications will readily occur to those skilled in the art.

Having described my invention, I claim:

1. In a microwave system; a coaxial transmission line comprising an inner conductor and a hollow outer cylindrical conductor; a helical transmission line comprising a helix of preselected diameter; and transition means for interconnecting said coaxial and helical transmission lines, said transition means comprising: an outer hollow cylindrical conductor having one end portion V-notched to form a multi-pronged crown-like section; and an inner conductor coaxially aligned with said outer conductor, said inner conductor including a cone-shaped helix terminating at the small-diameter end in a substantially straight coaxially-aligned conductor and terminating at the large-diameter end in a helical turn whose diameter is substantially equal to said preselected diameter of said helical transmission line, said cone-shaped helix of said inner conductor of said transition means being substantially coextensive with said multi-pronged crown-like section of said outer conductor.
2. In a microwave system; a traveling-wave tube including a helix having a mid-portion comprised of helical turns of preselected diameter and having at each end a cone-shaped portion comprised of helical turns of decreasing diameter terminating in a substantially straight conductor coaxially aligned with the axis of said cone-shaped end portion; external input and output coaxial transmission lines each having an inner conductor and an outer hollow cylindrical conductor; and means for connecting said coaxial transmission lines to opposite ends of said helix, said connecting means at each end comprising the connection of said inner conductor of said coaxial line to said straight conductor and the extension of decreasing portions of the

outer conductor of said coaxial line toward said helix beyond the point where said inner conductor and said straight conductor are connected.

3. In a microwave system; a traveling-wave tube including a helix having a mid-portion comprised of helical turns of preselected diameter and having at each end a cone-shaped portion comprised of helical turns of decreasing diameter terminating in a substantially straight conductor coaxially aligned with said cone-shaped end portion; external input and output coaxial transmission lines each having an inner conductor and an outer hollow cylindrical conductor; and means for connecting said coaxial transmission lines to opposite ends of said helix, said connecting means at each end comprising the connection of said inner conductor of said coaxial line to said straight conductor and the extension of decreasing portions of said outer conductor of said coaxial line toward said helix beyond the point where said inner conductor and said straight conductor are connected, said extended portion of said outer conductor being substantially coextensive with said cone-shaped end portion of said helix, said extended portion being so constructed that while the cross-sectional diameter is substantially constant the conductive area per unit length decreases in the direction of said helix.

4. In a microwave system; a traveling-wave tube including a helix having a mid-portion comprised of helical turns of substantially constant preselected diameter and having at each end a cone-shaped portion comprised of helical turns of decreasing diameter terminating in a substan-

5 10 15 20 25 30

tiably straight conductor coaxially aligned with the axis of said cone-shaped end portion; external input and output coaxial transmission lines each having an inner conductor and an outer hollow cylindrical conductor; and means for connecting said coaxial transmission lines to opposite ends of said helix, said connecting means at each end comprising the connection of said inner conductor of said coaxial line to said straight conductor and the extension of decreasing portions of said outer conductor of said coaxial line toward said helix beyond the point where said inner conductor and said straight conductor are connected, said extended portions of said outer conductor forming a multi-pronged structure substantially coextensive with said cone-shaped end portion of said helix.
